UNITED STATES PATENT OFFICE.

GUSTAVE F. IIITZELBERGER, OF NEW YORK, N. Y., ASSIGNOR TO THE AMERICAN ELECTRICAL NOVELTY AND MANUFACTURING COMPANY, OF SAME PLACE.

DESIGN FOR A PORTABLE LAMP-BODY.

SPECIFICATION forming part of Design No. 29,939, dated January 3, 1899.

Application filed December 3, 1898. Serial No. 698,222. Term of patent 14 years.

To all whom it may concern:

Be it known that I, GUSTAVE F. IIITZELBERGER, a citizen of the United States, residing in the borough of Brooklyn, city of New York, county of Kings, and State of New York, have invented and produced a new and original Design for Portable Lamp-Bodies, of which the following is a specification, reference being had to the accompanying drawings, forming a part of this specification, in which—

Figure 1 is an elevation of a lamp-body constructed according to my design. Fig. 2 is a front view thereof.

As shown in the drawings, the leading and essential feature of this design consists of a unitary lamp-body of cylindrical shape, elongated in the direction of its axis and having a bull's-eye at the forward end thereof.

The lamp-body is intended for use in a portable electric lamp, and in the particular form shown in the drawings consists of an elongated cylinder A, having a bull's-eye B at its forward end and being surrounded at each end and at the middle by a metallic ring C, the cylinder having a ring D attached to one side thereof.

Having described my design, what I claim, and desire to secure by Letters Patent of the United States, is—

The design for a portable lamp-body herein shown and described.

GUSTAVE F. IIITZELBERGER.
